H. ELLIS

KEY LEVER TENSION FOR TYPEWRITERS

Original Filed Feb. 5, 1919

Inventor,
Haleston Ellis
Att'y.

UNITED STATES PATENT OFFICE.

HALCOLM ELLIS, OF NEWARK, NEW JERSEY.

KEY-LEVER TENSION FOR TYPEWRITERS.

Original application filed February 5, 1919, Serial No. 275,118. Divided and this application filed February 19, 1923. Serial No. 620,089.

To all whom it may concern:

Be it known that I, HALCOLM ELLIS, a citizen of the United States, residing at Newark, in the county of Essex and State 5 of New Jersey, have invented certain new and useful Improvements in Key-Lever Tensions for Typewriters, of which the following is a specification.

This invention relates to tensioning means 10 for the key levers of typewriters, and the present application is a division of my application Serial No. 275,118, filed Feb. 5, 1919, now Patent No. 1,446,338, dated February 20, 1923.

15 The present improvements enable the returning springs of the key levers of a typewriter to be simultaneously tensioned by a simple and convenient operating device to suit the touch of the user, thereby enabling 20 the user of the machine to change the tension of all the key lever returning springs at will and so that the tension on all of the springs is substantially the same.

A practical embodiment of my invention 25 comprises independent suspension coil springs, one for each of the key levers, a movable member to which said springs are connected, and adjusting means, such, for instance, as a thumb screw, for moving said member to vary the tension on the springs.

While the present improvements are illustrated in connection with a typewriter, such as disclosed in my patent aforesaid, this is done for the purpose of disclosing a practical embodiment of the invention and relationship to the parts of a typewriter and not by way of limitation of the invention as the latter may be used on any typewriter 35 employing pivoted key levers.

40 The invention is susceptible of modification and is not limited to the specific embodiment described hereinafter and disclosed in the drawing.

The accompanying drawing is a vertical 45 longitudinal section through a typewriter provided with my present improvements.

The key levers, of which there are four different lengths, as usual, are shown at 1. The key levers are pivoted on a wire 2 extending across the machine at the rear and are held in normal, raised, position by suitable suspension contractile coil springs 3, 50 one for each key lever.

A swinging plate 4 is hinged on the back

rail 5 of the typewriter frame in any suitable manner, for instance, as shown at 6.

The upper ends of the respective springs 3 are hooked over and suspended from a single rod 7 which extends across the rear of the machine and is carried by the swinging 60 plate, 4. A thumb screw 8, which bears on the back rail 5, has a screw threaded engagement at 9 with a member carried by the swinging plate 4.

On turning the thumb screw 8 in one direction, the swinging plate 4 will swing toward the left, thereby diminishing the tension on the suspension coil springs 3. When the thumb screw 8 is turned in the opposite direction, it will draw upon the swinging 70 plate 4 and swing the latter toward the right, thereby increasing the tension on the suspension coil springs 3.

My invention does away with the necessity 75 of independently adjusting the tension of the returning spring of each key lever of a typewriter and affords means by which the user can instantly regulate the tension to suit the individual touch of the user.

In the machine illustrated, the type bars 80 are shown at 10 as pivoted on the wire 11 in the shiftable type basket 12 which is raised by the arm 13 carried by shaft 14 and operated by one or the other of two shift keys 15 of which only one is shown. 85 The connection between the respective key levers 1 and type bars 10 comprises a bell crank lever 16 pivoted at 17 and having a slot and pin connection at 18 with the key lever 1. A link 19 pivoted to the type bar 90 10 at 20, is hooked over a pin 21 on the bell crank lever 18.

What I claim is:—

In a typewriter, the combination with its frame, and key levers, of a swinging plate 95 hinged on the frame and disposed above the key levers, a single rod carried by said plate above, and crosswise of, the key levers, suspension coil springs connecting said rod to the several key levers, and an adjusting 100 screw engaged with the frame and plate, adapted to shift said plate to thereby simultaneously adjust the tensions of all of the springs.

In testimony whereof I affix my signature.

HALCOLM ELLIS.
